UNITED STATES PATENT OFFICE.

JOHN SCHREINER, OF CHICAGO, ILLINOIS, ASSIGNOR TO PAUL W. KOCH & COMPANY, OF CHICAGO, ILLINOIS, A CORPORATION OF ILLINOIS.

CONDUIT-BENDING MECHANISM.

Application filed November 27, 1925. Serial No. 71,594.

My invention, in general, relates to bending apparatus, and more particularly to conduit bending mechanism.

The object of the present invention is to 5 provide simple, inexpensive and compact bending mechanism particularly adapted for use in conjunction with pipe vises.

In the accompanying drawings,

Fig. 1 is a plan view of a pipe vise having applied thereto my novel conduit bending mechanism;

Fig. 2 is a front view of the mechanism illustrated in Fig. 1;

Fig. 3 is a side view of the mechanism illustrated in Figs. 1 and 2;

Fig. 4 is a sectional view taken on the line 4—4 of Fig. 1; and

Fig. 5 is a detailed view of a bending block or die.

Referring now to the drawings in detail, in which like reference numerals designate similar parts throughout the several views, 10 denotes generally a pipe vise which may be of any suitable or usual construction and comprises an upper part 11 and a lower part 12 (Fig. 2). The upper part is preferably U-shaped and is adapted to have one of its legs pivoted to the lower part 12. In Fig. 2 I have illustrated the leg 13 of the U-shaped part 11 as being pivotally attached to the lower part 12 by a bolt and nut 14. It is of course evident that by removing the bolt and nut 14 the U-shaped part 11 may be turned around and its leg 13 may be secured to the other side of the lower part 12. The other leg 15 of the U-shaped part 11 has pivotally attached thereto at 16 a latch 17 adapted to engage with a projection 18 on the lower part 12. By lifting the latch 17 away from the projection 18, the U-shaped part 11 may be moved about its pivot bolt 14 into a tilted position to permit pipes or conduits to be placed on the lower part 12 or removed therefrom, as the case may be, with facility.

The lower part 12 is equipped with a pair of stationary gripping jaws 20, and the upper part is provided with a movable jaw 21 disposed in a vertical plane passing through the space separating the pair of jaws 20 of the lower part 12. The upper jaw 21 is secured to a cross-piece 22 adapted to slide up and down in between the two legs 13 and 15 of the U-shaped part 11. The leg 13 has formed thereon a guiding rail 24 and

the leg 15 has formed thereon a guiding rail 25, which rails serve to guide the movement of the cross-piece 22. Attached to the cross-piece 22 is an end of a threaded member 26 which extends through a threaded aperture in the upper part of the part 11. The upper end of the threaded member or screw 26 is adapted to have inserted therein or attached thereto an element for turning the same in a manner well known to those familiar with the present art. Obviously, by turning the screw or threaded member 26, the jaw 21 may be moved with respect to the stationary jaws 20.

The lower part 12 of the pipe vise 10 has cast integral therewith an extension or block 30, (Fig. 3). This block 30 has formed therein two intersecting rectangular apertures 31 and 32. The aperture 32 is disposed in substantially a vertical plane and the aperture 31 is disposed in a longitudinal plane at right angles to the aperture 32. The block 30 is equipped with an apertured lug 33 which may be used with lugs 34 on the lower part 12 to fasten the vise and bending mechanism to a suitable bench or other supporting platform.

Associated with the block 30 is what I shall hereinafter refer to as a die block 35. This block is equipped with an arcuate edge 36 having formed therein an arcuate groove 37, which groove is of the same contour as that of the bend desired.

The die block 35 is also equipped with arcuate shaped aperture 38 which tends to lighten its weight. The block 35 is detachably mounted to the block 30 and may be replaced by other sized blocks of similar construction, obviously the size of the block used depends upon the type of bend desired. Each block 35 is provided with a rectangular shaped aperture 40 which is substantially the same size and contour as the apertures 31 and 32 in the block 30. In Fig. 5 I have illustrated a different size of block 35 which, with the exception of the degree of bend, is substantially like the block illustrated in Fig. 3. Therefore, it is the belief that the same reference numeral may be used to designate similar things in both the blocks.

In Fig. 4 I have illustrated the block 35 as being disposed in substantially a vertical position with its aperture 40 in alignment with the aperture 31 in the block 30. The block 35 is held to the block 30 by a rec-

tangular shaped rod 41 extending through both the aperture 31 in the block 30 and the aperture 40 in the block 35. The arcuate-shaped groove 37 in the block 35 connects 5 with a relatively straight groove 42 which is in alignment with the vortex of the lower pair of jaws 20 in the part 12 of the pipe vise 11. I have indicated by the reference numeral 45 a pipe or conduit to be bent. 10 This conduit is illustrated in Fig. 3 as being gripped by the jaws of the pipe vise in the usual manner. The conduit is disposed in a substantially horizontal position and rests in the groove 42 of the die block 35.

In Fig. 4 I have illustrated in dotted lines the manner in which the block 35 may be carried by the block 30 when it is disposed in a horizontal rather than in a vertical 20 position. In that event, the groove 41 of the die block 35 is positioned in alignment with the upper end of the rectangular aperture 32 in the extension or block 30. The rod 41 is then mounted in a vertical 25 position in the two aligned apertures 40 and 32. It is evident that although the die block 35 is mounted in a horizontal plane, the groove 42 thereof will still be in alignment with the bottom of the vise 30 jaws 20, so as to accommodate the conduit 45 to be bent. The rectangular rod 41 is prevented from falling out of the aligned aperture when it is disposed in a vertical 35 position by the top of the bench or platform upon which the vise is mounted. In practice, I find it necessary to mount the die block 35 in a horizontal plane when the conduit to be bent is relatively long, so as to prevent the end of the conduit from hitting the floor. For short lengths of conduits, the mounting illustrated in Fig. 3 will 40 be found to be satisfactory.

Now I shall proceed to describe in detail the actuating member by which I bend conduit 45. This member is indicated generally by the reference numeral 50 and is best illustrated in Fig. 3. It comprises a bifurcated arm 51 having a pair of parallel legs 52 which are adapted to straddle the die block 35, as well as the conduit 45. Rotatably mounted intermediate the legs 52 of the arm 51 is a roller 53 having a groove 54. The roller 53 is rotatably carried on a pin 55 mounted at opposite ends in the legs 52 of the arm 51. I preferably provide the legs 52 of the arm 51 with a plurality of apertures 56, so as to enable the roller 53 to be mounted in different positions with respect to the die block 35 to permit it to 55 accommodate different sizes of conduits 45. The groove 54 of the roller 53 is adapted to accommodate the top surface of the conduit 45, and the groove 37 in the block 35 is adapted to accommodate the lower surface 60 of the conduit 45.

Each of the die blocks 35 is equipped with a small bore 60 (Fig. 5) for receiving a pivot pin 61 (Fig. 3) which projects at opposite ends into suitable apertures in the legs 52 of the arm 51. This pivot pin 61 70 constitutes a pivotal mounting for the arm 51. It is apparent that by moving the arm 51 from the vertical position illustrated in Fig. 3 to the horizontal dotted position, the conduit 45 must, of necessity, be bent to conform with the arcuate shaped groove 37 in the die block 35. This is accomplished by the roller 53, as will be more fully described in the operation of my mechanism.

The upper end of the arm 51 is preferably reduced, as indicated at 64, in order to enable an ordinary pipe section to be telescoped thereby. That is to say, by mounting a pipe such as that illustrated in dotted lines in Fig. 3 and designated by the reference character 65 upon the reduced portion 64 of the upper end of the arm 51, it may be used as a handle for actuating the arm. Then, too, the pipe 65 provides additional leverage, thereby increasing the amount of force applied upon the portion of the conduit 45 being bent.

The operation of my bending mechanism is as follows:—

In the first place, the conduit vise 10 95 which, as has been previously mentioned, is of any usual or suitable construction, is mounted upon the bench and fastened thereto by means of the lugs 34 and the lug 33 on the block 30. Then the die block 35 is associated with the block 30 in either its vertical or longitudinal position, depending upon the size, or rather the length of the conduit being bent. The size of the block 35 employed, will depend upon the degree of 100 bend desired. It is evident that the only difference in the block 35 will be in the shape of the arcuate shaped groove 37 thereof. By employing my novel die block, a conduit may be bent into any shaped angle 110 desired. The size of the angle of course will depend upon the contour of the groove 37 of the die block.

After the die block 35 is mounted and placed upon the block 30 and held thereto by the rectangular rod 41, a section of conduit to be bent is placed thereon with an end extending through the jaws of the vise 10. The screw or threaded member 26 is then actuated to bring the jaws of the vise 115 into tight engagement with the section of conduit fastened thereto to tightly hold it in place.

Then the actuating member 50 is placed in position with its legs 52 straddling the conduit and the block 35, and the pin 61 is inserted therein and in the bore 60 in the die block 35, thus providing a pivotal mounting for the actuating member. A section of pipe 125 is then placed over the reduced end 64 of the 130

member 50, putting it in a condition for operation.

Then the operator pulls the section of pipe 65 in a direction away from the vise 10, causing the roller 53 to bend the portion of the conduit 45 contacting therewith downwardly, causing it to assume the contour of the groove 37 in the die block 35.

To remove the bent pipe, the vise jaws 10 are released by the screw 26, and the actuating member 50 is removed from the die block 35. The bending mechanism is then in a position to receive the next conduit to be bent. Should it be desired to use a different size die block, the one in use previously may be easily detached from the block 30 by removing the holding rod 41 and another die block 35 may be substituted therefor and the rod 41 inserted therein.

Now it is evident that during the process of bending the pressure is applied to the conduit to progressively bend same. That is to say, the pressure is moving in an arcuate path and hence must be progressively applied to the conduit. Contemporaneously with and during the aforesaid pressing action, the conduit is confined peripherally at the point the pressure is applied to the conduit to prevent distortion of the conduit and to cause it to maintain a symmetrical cross-section throughout the bend.

In practice, I find that with my novel bending mechanism, I am enabled to bend conduits into many different shapes without crimping or distorting the circular shape of the conduit at the place of the bend. This is a decided advantage over prior bending mechanisms for use in conjunction with conduits, since, from experience, I find that with the use of the prior types of bending apparatus the conduit was usually badly distorted at the place of the bend.

I desire it understood that although I have disclosed and described in detail the preferred embodiment of my invention, that the invention is not to be limited thereby, but only in so far as defined by the scope and spirit of the claims hereto attached.

I claim:—

1. In combination, a vise for gripping a conduit to be bent, an extension associated with the vise having a pair of apertures disposed at right angles to each other, a die block having an aperture, a rod insertible

in the aperture in the block for connecting it to the extension through the apertures in the said extension, the said block being attachable to the vise in a horizontal as well as in a vertical position, the said die block having an arcuate groove for defining the shape into which the conduit is to be bent, an arm having a pair of spaced legs straddling the said die block, a roller intermediate the said legs revolvably carried thereby and contacting with the conduit to be bent, and a pivotal connection between the legs of the arm and the die block for enabling the arm to be moved in an arcuate path to cause the roller thereof to press the portion of the conduit associated therewith into an arcuate shape defined by the arcuate groove in the die block.

2. In combination in a conduit bending device, a vise for gripping conduit to be bent, an extension associated with the vise having a pair of apertures disposed at right angles to each other, a die block having an aperture, and an element insertible in the aperture in the block for connecting it to the extension through the apertures in said extension, the said block being attachable to the vise in a horizontal as well as in a vertical position.

3. In combination in a device for bending conduit, a vise including a plurality of jaws for gripping conduit to be bent, a die block having an arcuate shaped groove in alignment with the jaws of the vise, and means associated with the vise for enabling the die block to be connected thereto in a plurality of different positions, said die block being of a given size and being readily detachable from said vise to enable its replacement by a different size of die block.

4. In combination in a conduit bending device, a vise including jaws for gripping a conduit to be bent, and a die block having an arcuate shaped groove, one end of which is in alignment with the jaws of the vise to receive a portion of the conduit gripped by the vise jaws, said die block being adapted to be used in conjunction with the vise to enable the conduit to be bent in two different planes.

In witness whereof, I hereunto subscribe my name this 23rd day of November, 1925.

JOHN SCHREINER.
